DESIGN FOR A BAPTISMAL ROBE OR THE LIKE

Martha B. Leavell, Nashville, Tenn.

Application July 9, 1948, Serial No. 147,476

Term of patent 14 years

(Cl. D3—26)

To all whom it may concern:

Be it known that I, Martha B. Leavell, a citizen of the United States of America, residing at Nashville, in the county of Davidson, State of Tennessee, have invented a new, original, and ornamental Design for a Baptismal Robe or the like, of which the following is a specification, reference being had to the accompanying drawing, forming part thereof.

Fig. 1 is a front view in elevation of a baptismal robe or the like, showing my new design.

Fig. 2 is a back view in elevation of a baptismal robe or the like, and

Fig. 3 is a view in perspective of the front of a baptismal robe or the like with the collar in open position and the sash untied.

I claim:

The ornamental design for a baptismal robe or the like, as shown.

MARTHA B. LEAVELL.
